AUTOMOBILE LAMP LENS HOUSING

Henry T. King and Harold W. Pilkey, Detroit, Mich.,
assignors to Chrysler Corporation, Highland Park,
Mich., a corporation of Delaware

Application February 4, 1955, Serial No. 34,360

Term of patent 7 years

(Cl. D48—32)

Fig. 3.

Fig. 4.

Fig. 3.

Fig. 4.

Fig. 1 is a front elevational view of an automobile lamp lens housing showing our new design;

Fig. 2 is a plan view thereof;

Fig. 3 is a side elevational view thereof;

Figs. 4, 5, 6, 7 and 8 are sectional views taken on the lines 4-4, 5-5, 6-6, 7-7 and 8-8 respectively of Fig. 1; and

Fig. 9 is a perspective view thereof on a reduced scale wherein the broken lines indicating the portion of an automobile are for illustrative purposes only.

We claim:

The ornamental design for an automobile lamp lens housing substantially as shown and described.
